UNITED STATES PATENT OFFICE.

DAVID SMITH, OF FALL RIVER, MASSACHUSETTS, ASSIGNOR TO HYDRO CARBON BURNER MANUFACTURING COMPANY, OF NEWPORT, RHODE ISLAND, A CORPORATION OF RHODE ISLAND.

HYDROCARBON-OIL BURNER.

Application filed April 26, 1922. Serial No. 556,705.

To all whom it may concern:

Be it known that I, DAVID SMITH, a citizen of the United States, and resident of Fall River, in the county of Bristol and State of Massachusetts, have invented a new and Improved Hydrocarbon-Oil Burner, of which the following is a full, clear, and exact description.

This invention relates to a hydro-carbon burner, and particularly to an improved burner which burns efficiently with a low grade of oil.

The invention also refers to burners in which the oil is broken up while under pressure, and mixed with air immediately previous to its ignition.

The object of the invention is to provide an improved, simplified burner structure, which is inexpensive to manufacture, and which may be readily adjusted to secure different results.

Another object of the invention is to provide a burner, using oil under pressure, and mixing the same with air in such a manner as to produce a substantially perfect combustion.

In the accompanying drawings;

Figure 1 is a longitudinal vertical sectional view through a burner disclosing one embodiment of the invention.

Figure 2 is a front view of the structure shown in Figure 1.

Referring to the accompanying drawing by numerals, 1 indicates a support of any kind, provided with a number of openings 2 through which air will pass into and through the openings 3 of the burner casing 4. If desired, air may be forced into these openings under pressure by any suitable means.

The casing 4 is provided with a tubular extension 5, threaded exteriorly at 6, and formed with a central boss 7 acting as a bearing for the rotating shaft 8, driven by any suitable power or mechanism at a comparatively high speed. The boss 7 is provided with oil passages 9 which merge into a lateral passage-way 10 connected to any suitable source of supply. Preferably the oil forced into the passage-way 10 is under some considerable pressure, and is discharged into the chamber 11, which chamber is preferably maintained filled with

a fuel, which fuel moves therefrom through the various passage-ways 12 in the spider 13. 55

This spider is preferably secured to the shaft 8 and is formed integral with a frusto-conical shaped nozzle 14, and this nozzle, at the inner end has a sliding fit with the boss 7, and the outer end is chamfered at 60 15, whereby the fuel passing therefrom may spread to any desired extent. It will be observed that the different webs 16 of the spider 13, act as beading or emulsifying members for the fuel which may be crude 65 oil, or any desired form of oil. In order to cause the webs 16 to perform their function more thoroughly, the same are constructed substantially diamond-shaped in cross section as illustrated in dotted lines 70 in Figure 1. Surrounding the nozzle 14 is an air nozzle 17 which, at the discharge end of the mouth 18, is only slightly larger than the outer end of the nozzle 14, while the inner end is much larger, and is internally threaded so as to be secured onto the threaded section 6. 75

Suitable set screws 19 are provided for locking the nozzle 17 in different adjusted positions. When the parts are set as shown 80 in Figure 1, and the burner is in operation, a certain flame will be produced, but if the nozzle 17 is moved outwardly so that the mouth or end 18 is nearer the outer end of the nozzle 14, the flame will change its shape 85 and become longer, while if the nozzle 14 was moved back, or away from the outer end of the nozzle 14, the flame would flare to a greater extent.

It will be noted that the diamond-shaped construction of the webs or lacerations 16, and the rotation of the nozzle or cup 14, produces a film of oil by centrifugal force, so that there is a circular sheet of emulsified or lacerated oil discharged from the nozzle 14 90 to mix with the air passing out the opening 18. It will of course be understood that the pressure of the oil, and the pressure of the air may be varied as circumstances may demand to secure the best burning action, and 100 the highest efficiency.

I claim:

1. An oil burner, comprising a base having an external screw-threaded cylindrical portion and a central hub concentric with 105 the cylindrical portion and projecting for-

- wardly therein, an air nozzle adjustable on the threaded portion of the casing, a shaft projecting through the hub, a cup fixed to the shaft and having its inner reduced end 5 mounted to turn upon the hub, and an annular shoulder on the hub against the extreme inner end of the cup, said base having air inlet passages therein and said base and hub having an oil duct, the legs of which 10 are at an angle to each other.
2. An oil burner, comprising a base having an external screw-threaded cylindrical portion and a central hub concentric with the cylindrical portion and projecting forwardly therein, an air nozzle adjustable on the threaded portion of the casing, a shaft projecting through the hub, a cup fixed to the shaft and having its inner reduced end mounted to turn upon the hub, an annular shoulder on the hub against the extreme inner end of the cup, said base having air inlet 15 passages therein and said base and hub having an oil duct, and a spider integral with the cup and having its central portion secured to the shaft and its radial portions 20 constituting lacerators.
3. An oil burner, comprising a base having an external screw-threaded cylindrical portion and a central hub concentric with the cylindrical portion and projecting forwardly therein, an air nozzle adjustable on the threaded portion of the casing, a shaft projecting through the hub, a cup fixed to the shaft and having its inner reduced end mounted to turn upon the hub, an annular shoulder on the hub against the extreme inner end of the cup, said base having air inlet 25 passages therein and said base and hub having an oil duct, and a spider integral with the cup and having its central portion secured to the shaft and its radial portions 30 constituting lacerators. 35
